UNITED STATES PATENT OFFICE

96,311

DESIGN FOR AN ELASTIC BRAID

Otto Eugene Huber, Reading, Pa., assignor to The
Narrow Fabric Company, West Reading, Pa., a
corporation of Pennsylvania

Application May 20, 1935, Serial No. 56,929

Term of patent 7 years

To all whom it may concern:

Be it known, that I, Otto Eugene Huber, a citizen of the United States of America, residing at Reading, in the county of Berks and State of Pennsylvania, have invented a new, original, and ornamental Design for an Elastic Braid, of which the following is a specification, reference being had to the accompanying drawing, forming part thereof.

Figure 1 shows one side of a portion of an elastic braid embodying my ornamental design, to which no tension is applied, the opposite side of

the fabric presenting the same ornamental appearance.

Fig. 2 discloses a part only of the elastic braid, shown in Fig. 1, as it appears when subjected to tension substantially equivalent to that incident to normal usage.

I claim:

The ornamental design for an elastic braid as shown and described.

In testimony whereof I affix my signature.

OTTO EUGENE HUBER.
